ARTICLE SUPPORT

Filed Nov. 8, 1927

UNITED STATES PATENT OFFICE

DANIEL O. SNYDER, OF MUNCY, PENNSYLVANIA

ARTICLE SUPPORT

Application filed November 8, 1927. Serial No. 231,881.

The present invention relates to a structure which may be broadly referred to as an improved article support, the same having more particular reference to a structure of this class which may be employed as a bag holder, or receptacle suspension means.

This invention is an improvement upon the foldable bracket construction shown in the J. C. Stugard patent identified by 1,565,118 10 and bearing date of December 8, 1925.

My primary aim is to generally improve such prior patent by providing a structure which is characteristically different and one which embodies a quick separable coupling 15 which is more sturdy, easy to manipulate, and dependable in operation.

An outstanding structural feature and important object is in the precise construction of an improved hanger bracket embodying a 20 novel arrangement of keeper seats, and an article suspension band with a keeper capable of ready engagement with the keeper seats.

A further improvement is the novel bag holder or suspension device individualized by 25 a somewhat ovate band and hingedly mounted retainers cooperable therewith to facilitate attachment and detachment of the bag.

Other features and advantages will become more readily apparent from the following description and drawings. In the drawings:—

Figure 1 is a side view with portions broken away and shown in section, disclosing the bag suspension means and supports therefor.

Fig. 2 is a top plan view of the structure seen in Fig. 1.

Fig. 3 is a fragmentary detail perspective view more clearly illustrating the improved hanger bracket and keeper means for association therewith.

Fig. 4 is a fragmentary detail view of a portion of the bag suspension device.

Fig. 5 is a side elevational view of a receptacle support.

Fig. 6 is a perspective view of the keeper.

Now referring to the drawings by reference characters, it will be observed that the numeral 6 designates generally, the improved hanger bracket. This comprises an attaching plate 7 properly apertured to permit it to

be bolted or otherwise fastened on the wall or other support.

The attaching plate 7 is provided with an integral arm extending at right angles therefrom. The arm is designated by the reference character 8, and said arm at its upper forward edge is provided with a slot 9. Opening inwardly and downwardly from the slot 9 is provided a substantially diagonally disposed pocket 11, the said slot 9 providing an entrance for the pocket 11. The arm 8 below the entrance 9 is provided on opposite sides of the pocket 11 with notches 10 opening at their opposed ends into the pocket 11. The notches 10 are disposed in horizontal alignment and constitute keeper seats, as will be hereinafter made more apparent.

Different types of article supports are employed in association with the hanger brackets. In the drawings, I have shown two different forms, for example, in Figs. 1, 2 and 4, we see a bag holder and in Fig. 5 we observe a pail or receptacle support.

Incidentally, the bag holder is generally designated by the reference character 12, 75 while the pail holder is identified by the reference numeral 13. Moreover the bag is indicated at 14, while the pail is represented at 15.

Considering the bag holder more in detail, it will be seen that this comprises a substantially ovate metal band 16, whose end portions are directed at right angles and into spaced parallelism as indicated better in Fig. 2 by the numerals 17. An elongated block 18 of the configuration shown in Fig. 6, 85 is riveted or otherwise fastened between the spaced extensions, and constitutes a keeper for reception in the keeper seats 10. The association of the keeper block 18 and the extensions 17 is such that the extensions may 90 straddle the outstanding arms 8 of the hanger bracket.

Obviously, these details provide a novel separable coupling between the hanger bracket and the article support whether it be 95 a bag holder or a bucket holder. It is evident that by placing the band 16 at an upwardly inclined angle with respect to the bracket arm in Fig. 1, the keeper block 18 can be inserted down through the opening 9 100

and slid down into the pocket 11. The pocket 11 provides sufficient clearance so that now the outer end of the keeper block can be set up against and into the forward keeper seat 10. Next, it is slipped back into the remaining keeper seat 10, so that the block now bridges the mouth of the pocket 11, as well as the entrance 9, thus effecting a rigid supporting connection between the bag holding band and the hanger bracket.

It is to be noted that the bag holder is of special form, in that it is provided with a pair of symmetrical clamping sections 19 having their end portions pivoted to the band 16 at 20. These sections are limited to upward swinging movement by the arrangement shown in Fig. 4, wherein it will be noted that the adjacent ends of the sections abut each other at 21, while the upper edges 20 of the abutting ends are cut off as at 22, to allow them to swing upwardly in the direction of the arrows. This facilitates placement of the mouth of the bag over the band 16 and underneath of the clamping sections.

25 In connection with Fig. 5, it is to be stated that the bucket supporting band 13 is of a shape to embrace the bucket. The band is constructed with the extension 17 and the keeper block 18 so that it can be substituted 30 for the bag holder by using the same kind of a hanger bracket 6. In other words, the hanger bracket may accommodate different characters of article hangers and supports. Moreover, with the arrangement shown, it is 35 possible to drop the article support down to the dotted line position shown in Fig. 1, so that it will be suspended in an entirely out-of-the-way position.

It is thought that the construction and advantages of the invention will be quite clear 40 after a careful consideration of the description in connection with the drawings, and therefore a more lengthy description is believed unnecessary.

45 Having thus described my invention, what I claim as new is:

1. In a structure of the class described, in combination, a hanger bracket embodying an attaching flange provided with an outstanding supporting arm, said arm being provided in its upper edge with a centralized entrance slot and being further provided below and at opposite ends of said slot with a pair of spaced notches opening in a direction 50 toward each other, said notches communicating with said slot and functioning as keeper seats, and an article suspension device embodying means embracing said arm and equipped with a keeper insertable 55 through said entrance slot and receivable in said keeper seats, whereby to cause said keeper to bridge said slot and to detachably connect said article suspension device with said arm.

6. 2. In a structure of the class described, a

hanger bracket provided with an attaching plate, having an outstanding supporting arm provided with opposed notches facing each other and functioning as spaced keeper seats, said arm also having a notch in its upper edge 70 above and located between said first named notches and forming an entrance in communication with said keeper seats, the arm being further formed below said keeper seats with an inwardly and downwardly cut out 75 portion providing a clearance pocket, and an article suspension device embodying means embracing said arm and equipped with a keeper block insertable through said entrance and receivable first in said pocket and 80 secondly in said keeper seats, whereby to provide a quick detachable connection between said device and arm.

In testimony whereof I affix my signature.

DANIEL O. SNYDER.
